UNITED STATES PATENT OFFICE.

SYLVESTER J. CHAPMAN, OF MARIETTA, OHIO.

ROAD-LEVELER.

No. 900,829.

Specification of Letters Patent.

Patented Oct. 13, 1908.

Application filed May 4, 1908. Serial No. 430,774.

To all whom it may concern:

Be it known that I, SYLVESTER J. CHAPMAN, a citizen of the United States, residing at Marietta, in the county of Washington and State of Ohio, have invented certain new and useful Improvements in Road-Levelers, of which the following is a specification, reference being had to the accompanying drawings.

10 My invention relates to improvements in road levelers and scrapers, commonly known as drags, and its object is to provide a simple and practical device of this character which may be effectively used upon clay roads and 15 which will be comparatively inexpensive in construction and strong and durable.

With the above and other objects in view, the invention consists of the novel features of construction and the combination and arrangement of parts hereinafter fully described and claimed, and illustrated in the accompanying drawings, in which

Figure 1 is a plan view of my improved road leveler; Fig. 2 is a front view of the 25 same; and Fig. 3 is a vertical front to rear section taken on the plane indicated by the line 3—3 in Fig. 1.

My improved road leveler or drag consists of two scraper bars or beams 1, 2 and a 30 packing bar or beam 3. These three beams are parallel to each other and are spaced apart and connected together by braces or cross bars 4 and tie rods or bolts 5. Said beams are also arranged in overlapping relation when viewed squarely from the front 35 of the device, in order that they may be angularly or diagonally disposed and in alinement with each other when drawn over the road. To insure the latter a draft chain 40 6 has its ends attached to eye bolts 7 adjacent to the ends of the foremost scraper bar 1 and the whiffletree 8 is provided with a chain or connection 9 having a hook 10 which may be engaged with any of the 45 links of the chain 6. It will be seen that by adjusting the hook 10 upon the chain 6 the diagonal angle of the bars or beams 1, 2, 3 with respect to the road may be varied as desired. The scraper bars 1, 2 are in the 50 form of planks and upon the front faces of their bottom portions are bolted or otherwise secured, as at 11, metal scraper blades or shoes 12 which effectively level the road.

The packing bar 3 is in the form of a heavy wooden beam the bottom of which is 55 smooth so that said beam will firmly pack the earth which is cut from the high points in the road and deposited in the hollows or low points by the scraper bars. The cross bars or braces 4 are arranged at right angles 60 to the bars or beams which they connect and their ends are reduced and shouldered, as at 13, and inserted in openings 14 formed in said bars or beams 1, 2, 3. Two of the bars 4 are preferably provided between each two 65 of said beams as shown and the tie bolts 5 are arranged adjacent to them so as to hold their reduced ends in said beams.

If desired, I may support a plank or board upon the cross bars 4 upon which the driver 70 may stand, as is common in devices of this character.

From the foregoing it will be seen that by arranging the two scraper beams and the packing beam in parallel and overlapping 75 relation and providing the draft connection as set forth, the device may be effectively used upon clay roads and its peculiar construction furthermore maintains it in proper position upon the road and reduces all tendency of it to shift laterally.

It will be further noted that the device is exceedingly strong and durable and owing to its simplicity may be produced at a comparatively small cost.

Having thus described my invention what I claim is:

A road leveler comprising two scraper beams and a packing beam arranged in parallel and overlapping relation, the packing beam being heavy and the scraper beams light, metal scraper blades upon the scraper beams, braces between said beams and having shouldered ends inserted in said beams, tie bolts between said beams, a draft chain 90 attached at its ends to the front scraper beam adjacent to the ends of the latter, and a whiffletree having a hook adjustably engaged with said chain.

In testimony whereof I hereunto affix my 100 signature in the presence of two witnesses.

SYLVESTER J. CHAPMAN.
